UNITED STATES PATENT OFFICE.

ANTONY SZABADOS, OF NEW MICHEL, BRITISH COLUMBIA, CANADA, ASSIGNOR OF
ONE-HALF TO HELENA MUELLER, OF NEW MICHEL, CANADA.

RAIL-JOINT.

1,021,955.

Specification of Letters Patent.

Patented Apr. 2, 1912.

Application filed October 6, 1911. Serial No. 653,143.

To all whom it may concern:

Be it known that I, ANTONY SZABADOS, a subject of the King of Hungary, residing at New Michel, Province of British Columbia, 5 Canada, have invented certain new and useful Improvements in Rail-Joints, of which the following is a specification, reference being had therein to the accompanying drawings.

10 This invention relates to rail joints, and the primary object of my invention is to provide a series of splice bars for connecting the confronting ends of rails, whereby the rails cannot become vertically or laterally displaced.

Another object of this invention is to obviate the necessity of using screw bolts and nuts which have a tendency to release the splice bars due to vibration of rails.

20 A further object of this invention is to provide a rail joint embodying a brace for the outer sides of rails, which will provide practically a continuous tread for rolling stock.

25 With the above and other objects in view, the invention resides in the novel construction, combination and arrangement of parts to be hereinafter specifically described and then claimed.

30 Reference will now be had to the drawings, wherein like numerals denote corresponding parts throughout the several views, in which:

Figure 1 is a side elevation of the rail joint; Fig. 2 is a plan of the same partly broken away and partly in horizontal section. Fig. 3 is an end view of a rail joint; Fig. 4 is a cross sectional view of the same; Fig. 5 is a perspective view of a detached outer splice bar; Fig. 6 is a similar view of an inner member of said bar; and Fig. 7 is a similar view of a locking member of said bar.

35 The reference numerals 1 and 2 denote the confronting ends of rails having the webs 3 thereof provided with openings 4.

50 5 denotes an inner splice bar resting upon the base flanges 6 of the rails 1 and 2 and bracing the heads thereof. The splice bar 5 is provided with openings 7 alining with the openings 4.

55 8 denotes bolts arranged in the openings 7 and 4, said bolts having heads 9 engaging the outer sides of the bar 5. Adjacent to the opposite ends of the bolts are annular

grooves 10 for a purpose that will presently appear.

11 denotes an outer splice bar adapted to rest upon the base flange 6 of the rails 1 and 2. The splice bar 11 has the upper edge 60 thereof provided with a web 12 engaging the outer sides of the heads of the rails, this web providing a continuous tread for rolling stock in passing from one rail to the other. The inner side of the splice bar 11 65 has an oblong housing 13, with one end thereof closed, as at 14, and the opposite end terminating at a point removed from the end of the bar 11. The housing 13 has a longitudinal slot 15, and the splice bar 11 70 at the open end of the housing 13 has an open slot 16 and a small opening 17. The splice bar 11 also has openings 18 adapted to register with the openings 4 and 7.

75 The reference numeral 19 denotes an inner member adapted to slide in the housing 13, said member having a longitudinal tongue 20 adapted to fit in the slot 15. The member has openings 21 adapted to register with the openings 18, 4, and 7. One end 80 of the member extends in close proximity to the closed end 14 of the housing, and the opposite end of the member has a head 22 adapted to fit against the open end of the housing 13.

85 23 denotes a locking member adapted to slide in a groove 24 provided therefor in the bar 11 between said bar and the member 19. This locking member has openings 25 in communication with slots 26, said openings 90 and said slots resembling key-holes. One end of the locking member 23 has an opening 27 adapted to register with the opening 17 of the bar 11, and the same end of said member has a T-shaped tongue 28 at right 95 angles to said member and adapted to ride in the slot 16 of the bar 11.

29 denotes a compression spring interposed between the closed end of the bar 11 and the end of the member 23.

100 30 denotes a pin adapted to be placed in the openings 17 and 27 to extend through one of the openings 25 of the member 23.

When the elements assemble in locked position, they are illustrated in Fig. 1, the bolts being maintained in the slots 26 by the action of the spring 29. The pin 30 extends through the bar 11 into the opening 25 at one end of the locking member 23 as shown in Fig. 1, the opening 27 in the lock- 110

ing member 23 being exposed through the slot 16 in the bear 11 as clearly shown in Fig. 1. It will be assumed that it is desired to separate the elements, the pin 30 is removed and the member 23 pushed inwardly which positions the bolts in the openings 25. This action compresses the spring 29. When the member 23 has been shifted so that the bolts are in the openings 25 of said member 23, the pin 30 is then inserted through the arm 11 and engages in the opening 27 whereby the member 23 is held from movement against the action of the spring 29. The bolts are then removed. When a new set of bolts have been placed in position, the pin 30 is removed from the opening 27 which releases the member 23, the spring 29 then acting to shift the member 23 outwardly whereby the bolts will enter the slots 26. The pin 30 is then placed in position thereby locking the member 23 from movement with respect to the bar 11.

The rail joint in its entirety is made of strong and durable metal, and the design of the splice bars is such as to allow for expansion and contraction.

What I claim is:

1. The combination with rails, having the webs thereof provided with openings, of an inner splice bar adapted to brace the inner sides of said webs at the ends thereof, bolts extending through said inner splice bars and the webs of said rails, said bolts having annular grooves formed therein, an outer splice bar, a housing carried by the inner side of said outer splice bar and having one end thereof closed, an inner member slidably mounted in said housing, a locking member slidably mounted between said inner mem-

ber and said splice bar, said splice bar and said member having openings formed therein to receive the grooved ends of said bolts with the openings of said locking member in communication with slots formed therein, whereby said locking member can be shifted to engage in the groove of said bolts and lock said bolts in engagement with said rails.

2. The combination with rails having the webs thereof provided with openings, of an inner splice bar adapted to brace the inner sides of said webs at the ends thereof, bolts extending through said inner splice bars and the webs of said rails, said bolts having annular grooves formed therein, an outer splice bar, a housing carried by the inner side of said outer splice bar and having one end thereof closed, an inner member slidably mounted in said housing, a locking member slidably mounted between said inner member and said splice bar, said splice bar and said member having openings formed therein to receive the grooved ends of said bolts with the openings of said locking member in communication with slots formed therein, whereby said locking member can be shifted to engage in the groove of said bolts and lock said bolts in engagement with said rails, means arranged in said housing and adapted to retain said locking member in an unlocked position, and means carried by said outer splice bars and adapted to lock said locking member in a locked position.

In testimony whereof I affix my signature in the presence of two witnesses.

ANTONY SZABADOS.
